Atty.

UNITED STATES PATENT OFFICE.

GERALD DRUMMOND, OF WORCESTER, ENGLAND.

DOUBLE-ACTING TWO-STROKE-CYCLE INTERNAL-COMBUSTION ENGINE.

Application filed June 2, 1923, Serial No. 643,048, and in Great Britain August 14, 1922.

This invention relates to an internal combustion engine operating on the Diesel principle, that is, wherein the heat of compression of air causes ignition of injected fuel. According to this invention, a power stroke is effected every half-revolution of the driven engine shaft. Further, the invention lends itself to the production of a compact power unit of clean external appearance and there are no reactionary thrusts on cylinder supporting members etc., such as are met with in many ordinary engines. The improved engine is easily balanced, and possesses the further advantage of controlled reversibility.

According to this invention, two pistons are mounted in a cylinder, slideable but unrotatable therein, and they are arranged co-operatively to drive a shaft parallel to the axis of the cylinder, through members engaging inclined surfaces formed on or rigidly with the shaft. The inclined surfaces are so arranged that the pistons reciprocate symmetrically, that is, they approach together, stop, move apart, stop, and repeat this cycle. The space between them forms one combustion chamber, and the spaces between the cylinder ends and pistons form two other chambers which are in effect one, and may if desired be connected by suitable ducts. Further, according to the invention, the shaft may be co-axial with the cylinder and pass through the pistons and cylinder end plates. In this case, the pistons are connected to sleeves which may slide but not rotate in glands in the end plates, and which carry at their outer ends anti-friction devices engaging inclined surfaces preferably in the form of grooves cut in the shaft, which rotates within the sleeves and preferably also within an insulating sleeve which protects it from the high temperature of the combustion chambers. The combustion chambers have valves for the emission and admission of gases and also fuel injection valves. The engine is provided with a fuel distributor which allows of timing the injection of fuel, as will be seen, and thus allows of reversal of the engine by timing. This device will be better understood from the following description of a preferred

form of the engine, wherein reference is made to the drawing, of which

Fig. 1 is a part-sectional elevation of the engine,

Fig. 2 is a sectional view of the distributor.

Fig. 3 is a sectional plan view of the same.

The engine shown is of horizontal type with one cylinder. It will be understood of course, that a plurality of cylinders may be used, coupled up or on one shaft, if desired.

The cylinder barrel 1 has pistons 2 mounted at the inner ends of sleeves 3 which pass through the end plates 4 through suitable packing glands 5. The sleeves 3 are splined or otherwise prevented from rotating as will be described. The outer ends of the sleeves carry housings in each of which is a free ball 6 preferably held in place by a threaded plug 7. The balls 6 run in grooves 8 formed in the thickened portions 9 of the engine shaft 10 which is co-axial with the cylinder 1. The grooves are in the form of interrupted helices each passing nearly half way around the shaft, and returning, so that a continuous track is formed in which a ball 6 runs. Reciprocation of the pistons causes rotation of the shaft and a flywheel 11 is fitted in the described form to carry the shaft over the dead-centres formed by the apices of the grooves. The grooves are so disposed that their apices correspond and are symmetrical at each end of the shaft, thus the pistons move symmetrically as stated.

Between the sleeves 3 and shaft 10 there is a sufficient space left for the insulating sleeve 12 which surrounds the shaft 10, and on which the pistons 2 slide. A suitable bearing 13 enables the shaft 10 to rotate easily within the sleeve and a space 14 is left between the insulating sleeve 12 and the shaft. This space may in some cases contain water or oil or other cooling medium forming part of a circulatory cooling system, to which the cylinder 1 and other parts may also be subjected if desired.

The outer ends of the shaft 10 are supported in suitable bearings 15 to lend stiffness to the overhanging portions. A train of pin-

ions 16 serves to drive camshafts 17, 18 on each side of the engine, the camshafts bearing cams 19 co-operating with rockers 20 which serve to open poppet valves 21 which are connected with the space between the pistons and the spaces between them and the end plates. The valves which are thus in effect two per chamber, are exhaust and air-inlet respectively. An air-pump, of any type usually used for Diesel engine service, injects air under compression into whichever chamber has an open inlet valve, and the ingoing air scavenges or helps to scavenge the products of the last explosion in that chamber, through the exhaust valve which is simultaneously opened or timed with overlap. From the camshaft 18 is driven a shaft 22 which drives the fuel distributor which is a feature of the invention. The distributor comprises a casing or chamber 23, with a coverplate 24 incorporating a pipe union 25 connected to the pressure-fed liquid fuel source. The chamber 23 has three leads 26 from it, disposed as shown, 90° apart and contains an annular block 27 which is partially rotatable say, through the medium of a boss 28 projecting through an arcuate slot in the casing 23. The interior of this block is cored out into a conical bore, and a conical valve member 29 rotated by the shaft 22, is shaped to conform with the interior of the block and to be a liquid-tight fit therein. The valve member 29 has two ports 30 disposed as shown at 180° and in the rotation of the member 29 the ports 30 register alternately with two opposite channels in the block 27 or with one channel between the opposed pair. The channels in the members 27 are made tapered or bell-mouthed with a narrower opening towards the valve member 29 than to the leads 26. Thus the block 27 may be rotated through a considerable angle, retarding or advancing the moment when a clear passage is opened between the interior of valve 29 and the leads 26. The pressure fed fuel is, of course, fed into the inside of the valve for distribution, whence it is allowed in the course of rotation of the valve member to flow either to the chamber between the pistons 2 or to the chambers at the ends of the cylinder. The fuel is actually admitted from the leads 26 to the cylinder through needle valves of the type shown or any other suitable type. As shown, a needle-valve stem 31 is provided in a pressure resisting housing 32, with its spring 33 all enclosed. The valve unit is screwed into the cylinder at 34 and so is easily removable as a whole. A spraying or other suitable jet may be provided if desired, and any known practice such as fuel projection on to a hot spot, may be incorporated, as will be obvious.

In the engine illustrated, the pistons are prevented from rotation by the provision on the sleeves 3 of a sliding block 35 running in a track 36 formed in the framework 37 of the

engine, the block and track co-operating to take the rotational reaction forces of the piston. Thus no torque is set up in the piston or its sleeve, and possibly undesirable forces arising therefrom are eliminated.

I claim:

1. An internal combustion engine having, in combination, a cylinder, a shaft disposed in the cylinder, two pistons oppositely disposed in the cylinder, means connecting the pistons to the shaft to convert reciprocating movement of the pistons into rotary movement of the shaft, means whereby the pistons are adapted to be reciprocated in the cylinder simultaneously towards and from each other, the portions of the cylinder on both sides of the pistons constituting combustion chambers, and a sleeve in the cylinder surrounding the shaft to constitute a heat insulator for the shaft. 70

2. An engine having, in combination, a cylinder, a frame having a fixed track, two members, one a shaft and the other a sleeve surrounding the shaft, the sleeve having a slide engaging the track to permit reciprocating movement of the sleeve and to prevent rotary movement of the sleeve, a piston fixed to the sleeve within the cylinder, one of the members having a continuous spiral groove and the other member having an element projecting into the groove, and means for reciprocating the sleeve longitudinally of the shaft to effect the rotation of the shaft through the groove-and-element connection. 75

3. An internal-combustion engine having, in combination, a closed cylinder, two pistons reciprocally mounted in the cylinder, the portions of the cylinder on both sides of the pistons constituting combustion chambers, each combustion chamber being provided with a valve, means for injecting fuel into the cylinder through the valves at predetermined times to effect simultaneous reciprocating movement of the pistons symmetrically towards and from each other in the cylinder at predetermined times, a fuel-distributing valve connected with the valves for advancing and retarding the injection of the fuel, and means controlled by the operation of the pistons for controlling the operation of the fuel distributor. 100

4. An internal-combustion engine having, in combination, a closed cylinder, a shaft disposed in the cylinder and projecting therefrom at each end thereof, a sleeve surrounding each outer end of the shaft, the sleeves being non-rotatably mounted with respect to the cylinder but being adapted to reciprocate longitudinally of the shaft, the outer end of each sleeve projecting through the corresponding end of the cylinder, a piston fixed to the inner end of each sleeve within the cylinder, the portions of the cylinder on both sides of the pistons constituting combustion chambers, the shaft being provided with two 105

continuous spiral grooves, the sleeves each having an element engaging in one of the grooves, whereby the sleeves are connected with the shaft to always convert reciprocating movement of the pistons and consequent longitudinal movement of the sleeves upon the shaft into rotary movement of the shaft, and means for injecting fuel in the intermediate disposed chamber and in the other

two chambers alternately to effect simultaneous reciprocating movement of the pistons symmetrically towards and from each other in the cylinder longitudinally of the shaft to effect the rotation of the shaft through the groove-and-element connections.

In witness whereof I have signed this specification.

GERALD DRUMMOND.
